UNITED STATES PATENT OFFICE.

EVERETT J. HARDGRAVE, OF SAN ANGELO, TEXAS.

COMBINATION LOCK.

Application filed November 30, 1923. Serial No. 677,872.

To all whom it may concern:

Be it known that I, EVERETT J. HARDGRAVE, a citizen of the United States, residing at San Angelo, in the county of Tom Green and State of Texas, have invented certain new and useful Improvements in Combination Locks; and I do hereby declare the following to be a full, clear, and exact description of the same, reference being had to the accompanying drawings, forming part of this specification.

This invention relates to a keyless or combination lock operable by pressing a series of tumblers in proper sequence so as to permit the sliding of a reciprocating member which may be a bolt, an electrical contact member, or a simple stop member. The principal object of the present invention is to provide a simple and efficient lock of the character described. A further object of the invention is to provide a simple mechanism for preventing access to the mounting screws when the device is in closed position while permitting ready access to such screws when the lock is in open position.

A further object of the present invention is the provision of a simple keyless lock having a plurality of tumblers, the axes of which are parallel to one another and lie in a single plane. A still further object of the invention is the provision of a simple lock that can be conveniently operated by the thumb and the four fingers of one hand.

While the lock is of general utility and will probably find its principal success in a control for the ignition and lighting system of an automobile, for convenience and simplicity of illustration the lock is shown in its simplest form, the sliding member as illustrated being a bolt for a closet door.

In the drawings,—

Figure 1 is a side elevation of the lock partly broken away and showing the bolt in locked position.

Fig. 2 is an end elevation of the device as shown in Fig. 1.

Fig. 3 is a view similar to that shown in Fig. 1, but illustrating the mechanism in unlocked position.

Fig. 4 is an end view of the device as shown in Fig. 3.

Fig. 5 is a top plan view with the top of the casing omitted.

Fig. 6 is a side elevation of one of the tumblers with its positioning slide. 55

Fig. 7 is a section taken on the line 7—7 of Fig. 1.

Fig. 8 is a plan view of the structure of Fig. 7.

Fig. 9 is a side elevation of the reciprocating member. 60

The back 10 of the lock is secured against the support 11, which is a door in the construction illustrated, by means of a plurality of mounting screws 12 and has a lower flange 14 projecting forward at right angles to the main portion of the back and having a small downturned retaining lip 15 to be received within the groove 16 formed by the upturned flange 17 of the casing 18. 70

The casing 18 has the usual side flanges 20 and a top flange 21 having a lip 22 extending the entire width of the lock and engaging the groove formed by the offsetting of the upper portion of the back 10, 75 thus preventing downward movement of the casing with respect to the back.

A plurality of short shafts shown in the drawings as four in number are secured to the casing 18 and the back 10, the axes of all four being parallel to one another and lying in the same plane. Three of these shafts each numbered 25 in the drawings are not rotatable, but the fourth shaft 26 is rotatable and projects somewhat beyond the casing 18 so as to receive a short handle 27 adapted to be moved by the thumb of the operator. On this shaft 26 is mounted a tumbler in the shape of a sector 5 secured thereto and in addition a second tumbler or sector 1 which is rotatable about the axis of the shaft 26, receiving its motion through a positioning slide 31 having a pivotal connection with the tumbler 1, this slide being 85 guided by a slot 32 in the forwardly projecting flange 14 of the back 10. This mechanism may best be seen in Fig. 4 and while the following description is particularly directed to tumbler 1 the description is 90 equally appropriate to the tumblers 2, 3, and 4; tumbler 5, as previously stated, differing in that it is fast to the shaft 26 and is operated by moving the handle 27.

The slide 31 has a lug 33 projecting through an orifice 34 forming a pivotal connection with the tumbler and also serving 100 105

to support slide 31 when the tumbler 1 is in its lowermost position where it rests by gravity, the lock in the very simple form shown having no springs of any kind. The lower 5 end of the slide 31 which projects through the flange 14 is bent to form a fingerpiece 36 which the operator presses upward to cause rotation of the tumbler about its pivot 26. The outer portion 37 of the tumbler is 10 secured to the hub or pivot portion by means of arms 38 and 39 so as to form an opening in the central portion of the tumbler. The outer edge 40 of the tumbler is preferably a true arc having the distance 15 of the pivotal axis of the tumbler as its radius. A projection 41 projects from the arc-shaped periphery 40 and serves to position the tumbler in the setting of the lock. The slot 42 communicates with the open 20 space in the center of the tumbler and when in correct position lies in registry with the shelf 44 of the reciprocating member or bolt 45.

Rotatably mounted on each of the shafts 25 25 are similar tumblers 2, 3, and 4, quite similar to tumbler No. 1, save that the radius of the arc 40 in each case is the distance from the arc 40 of tumbler No. 1, to the pivot of the respective tumbler, the radii 30 therefore of these tumblers increasing from left to right as seen in Fig. 1. From the foregoing it will be apparent that when the tumblers are in any position they will have their arcs at the same distance from 35 the shaft 26 measured in the plane of the four shafts.

A second point of difference is the provision of longer projections on the tumblers 2, 3, and 4, these projections being numbered 48 in the drawings and extending at 40 right angles to the main portion of the tumbler and extending to within a short distance of the bolt 45, each of these longer and L-shaped projections being positioned 45 very near the lower end of the tumbler in order that any one of the tumblers may be raised from its lowest to its highest position without touching the similar projections 48 on the other tumblers, this being 50 possible due to the different radii of the tumblers.

While I have shown the projections 41 and 48 as integral with the tumblers it will be understood by those familiar with the 55 art that these projections may be separate pieces and be adjustably mounted on the tumblers so as to provide the owner with a ready means of altering the combination when desired. I prefer, however, to make the projections integral with the tumblers and to alter the combination by the substitution of a complete tumbler, thus permitting the use of a much narrower lock casing. The positions of the slots 42 may be altered 60 65 in order to get the different combinations,

and if desired a number of additional nicks or shallow notches 49 may be cut along the inner edges of the portions 37 to avoid the possibility of aligning the slots by feeling with a slight pressure on the bolt. 70

The bolt 45 is, as usual, mounted in proximity to the back 10 and projects beyond one of the side flanges of the casing in open position and to the other side when in closed or locked position. In Fig. 3 the 75 device is shown in unlocked position with the bolt 45 extending to the left at which time the shelf 44 of the bolt is within the slot 42 of each one of the five tumblers, these 80 slots 42 being in registry and lying at this time in substantial alignment with the four shafts. The bolt in the form shown is not spring-pressed, but is manually controlled by means of a handle 50 mounted on an arm 51 integral with or secured to the bolt 45 85 passing through a slot 52 in the casing 18. In the position shown the handle 50 may be moved to the right which action will reciprocate the bolt 45 and remove the shelf 44 from engagement with the five tumblers, 90 allowing the latter to drop by gravity to their lowermost position.

A safety catch 55 is loosely pivoted to the casing 18 as at 56 and normally rests upon the flange 14, having an intermediate bowed portion 57 engaging such flange, the flat portion of this catch near the pivot end, however, lying entirely to one side of the flange 14. At its free end the catch 55 has a head 58 which just clears the arm 51 as the latter moves from side to side. This head 58 as shown in Fig. 3 lies entirely to one side (to the right) of the arm 51 so that the catch 55 may be freely turned about its pivot, the parts shown in this figure being as previously stated in unlocked position. When, however, the arm 51 is moved to the right to throw the bolt into locked position the arm 51 lies immediately above the head 58 and prevents all movement of the catch 55. Referring now to Fig. 7 it will be seen that the casing 18 can be removed from the back 10 only by raising the flange 14 so that the lip 15 may clear the upturned end 17 100 of the casing 18. When the bolt is in unlocked position as shown in Fig. 3 the flange 14 may easily be raised since the catch 55 105 will turn freely about its pivot, but when the bolt 45 is in locked position the flange 14 cannot be raised at all since the offset portion 57 of the catch engages the end of the flange 14 and the arm 51 of the bolt 110 engages the head 58 of the catch thus making it impossible to remove the casing 18 in order to tamper with the lock or to remove the mounting screws 12. 115

The operation of the device is as follows: With the parts as shown in Fig. 3 the bolt 45 may be moved to the right by means of 130

- the handle 50, this action moving the bolt to locked position with the arm 51 of the bolt immediately above the head 58 of the catch. In so moving the bolt the shelf 44 moves 5 from within the aligned slots 42 of the five tumblers and these tumblers drop by gravity to their lowermost positions. It is now possible to unlock the bolt without knowing the combination, since movement to the left 10 of the bolt will be prevented by the shelf 44 coming into contact with the inner edges of the portions 37 of the tumblers. The correct combination to open the lock shown in the drawings is 4, 1, 3, 5, 2. By raising the 15 tumbler 4 until it strikes the top flange 21 of the casing the slot 42 will be brought into correct registry, the L-shaped projection 48 on this tumbler lying somewhat above the plane of the top of the shelf 44. By next 20 raising tumbler 1, the projection 41 on this tumbler will engage the L-shaped projection 48 on tumbler 4 and will correctly position the slot of tumbler 1. It might be here noted that the fingerpiece controlling tumbler 4 25 may now be released since by holding the fingerpiece of tumbler 1, tumbler 4 will be held in contact with the top flange 21. Tumbler 3 is now raised by the fingerpiece 36 of its slide 31 until its L-shaped projection 30 48 comes into contact with the projection 41 on the tumbler 1. Tumbler 5 is now raised by means of the handle 27 until its short projection 41 contacts with the projection 48 on tumbler 3. By now raising 35 tumbler 2 until its projection 48 engages the projection 41 on tumbler 5 all of the slots 42 will be found in registry and the bolt 45 may now be shot to the left to unlock the device. It will be noted that but one tumbler 40 at a time may be pressed upward, owing to the interference of the projections one with another, the correct sequence being the key to the combination.

This is a substitute application for an application heretofore filed by applicant, Serial No. 536,171.

What I claim is:

1. A combination lock characterized by the provision of a sliding bolt and a series 50 of tumblers mounted on independent and parallel axes said tumblers having recesses therein adapted to be brought into registry with each other by movement transversely of the line of movement of the bolt.
- 55 2. A combination lock characterized by the provision of a sliding bolt and a series of tumblers mounted on independent and parallel axes, said axes all lying in a single plane said tumblers having recesses therein 60 adapted to be brought into registry with each other by movement transversely of the line of movement of the bolt.

3. A combination lock characterized by the provision of a sliding bolt and a plurality

of tumblers mounted on independent and 65 parallel axes, an adjustable tumbler having its pivot coaxial with one of said first mentioned tumblers, and a plurality of means each individual to a single tumbler for setting the lock said tumblers having recesses 70 therein adapted to be brought into registry with each other by movement transversely of the line of movement of the bolt.

4. A combination lock characterized by the provision of a plurality of sector shaped 75 tumblers of varying radii and cooperating projections on said tumblers.

5. A combination lock characterized by the provision of three manually operated sectors, each of said sectors having a radial 80 slot and a single projection on its arc-shaped periphery said projection being arranged to support one another when the sectors are in unlocking position.

6. A combination lock characterized by 85 the provision of a plurality of independently mounted finger operated tumblers mounted on independent parallel axes lying in the same plane, and a thumb operated tumbler having its pivot coaxial with one 90 of the first mentioned tumblers and positioned to co-operate with said finger operated tumblers.

7. In a combination lock, a reciprocating member, a back having a locking lip, a casing having a member engaging said locking lip, a safety catch pivoted to said casing and normally engaging a portion of said back in proximity to said lip, and means carried by said reciprocating member for 95 preventing movement of said catch when said reciprocating member is at one limit of its travel.

8. In a combination lock, a bolt having a plurality of laterally extending projections, 100 a plurality of sequence operated tumblers each having a slot adapted to be brought into registry with one of said projections, a detachable casing, a lever pivoted to said casing, said lateral projection on the bolt 105 lying in the path of movement of said lever when the bolt is in locked position to prevent removal of the casing.

9. In a combination lock, a bolt having a laterally extending shelf, a plurality of 110 tumblers each having an arcuate portion limiting the movement of said shelf, each of said arcuate members having a slot therein adapted to be brought into registry with the line of movement of said shelf, and a plurality of parallel positioning slides each 115 slide being pivoted to one of said tumblers.

10. A combination lock characterized by the provision of four independently mounted tumblers, a slide pivoted to each of said 120 tumblers, a fifth tumbler, and a lever for operating said fifth tumbler.

EVERETT J. HARDGRAVE.
